Fig. 3

Fig. 4

Fig. 5

Fig. 6

Fig. 7

Fig. 8

I claim:

The ornamental design for a vanity set, substantially as shown.
